SLEIGH OR SIMILAR ARTICLE

James L. Dobson, 60—15 Woodside Ave., Woodside, N.Y.

Filed Sept. 8, 1964, Ser. No. 81,627

Term of patent 7 years

(Cl. D34—15)

FIG. 1 is a side elevational view, partly in section, of the sleigh or similar article, showing my new design.

FIG. 2 is a top plan view thereof.

FIG. 3 is a rear view thereof.

FIG. 4 is a front view thereof.

FIG. 5 is a bottom view thereof.

I claim:

The ornamental design for a sleigh or similar article, substantially as shown.
